(57) **CLAIM**

The ornamental design for the handle for portable sterilizing apparatus, as shown and described.

DESCRIPTION

FIG. 1 is a perspective view of our new handle for portable sterilizing apparatus design;

FIG. 2 is a front elevation view thereof;

FIG. 3 is a rear elevation view thereof with the tray member removed in order to show the underlying surface of the handle for portable sterilizing apparatus;

FIG. 4 is an enlarged left side elevation view thereof;

FIG. 5 is an enlarged right side elevation view thereof;

FIG. 6 is a top plan view thereof; and,

FIG. 7 is a bottom plan view thereof.

The broken lines in the drawing figures depict unclaimed environmental subject matter in both full and partial states. The broken lines form no part of the claimed design.
